UNITED STATES PATENT OFFICE

ANDREW DELPH, OF POTTSVILLE, PENNSYLVANIA

LOUD-SPEAKER

Application filed December 30, 1926. Serial No. 158,049.

This invention relates to a horn construction and pertains particularly to an improved type of horn for use upon talking machines or as a loud-speaker for a radio set.

5 The primary object of this invention, is to provide, in a manner as hereinafter set forth, a loud-speaker horn having inherent qualities for materially improving the tone of signal vibration introduced thereto and amplifying these signals smoothly and without distortion.

Another object of the invention is to provide, in a manner as hereinafter set forth, a loud-speaker which will amplify signals passing therethrough, without imparting a harsh metallic tone thereto as is usual with loud-speakers of the type at present in use.

Numerous other objects and advantages will become apparent as the description of 20 the invention proceeds, and the invention will be best understood from a consideration of the following detailed description taken in connection with the accompanying drawings forming a part of this specification, with the 25 understanding however, that the invention is not confined to any strict conformity with the showing of the drawings but may be changed or modified so long as such changes or modifications mark no material departure 30 from the salient features of the invention as expressed in the appended claims.

In the drawings:

Figure 1 shows the loud-speaker embodying this invention in front elevation.

35 Figure 2 is a side elevational view of the speaker.

Figure 3 is a vertical longitudinal section of the structure, and

Figure 4 is a transverse section taken upon 40 the line 4-4 of Figure 3.

Referring now to the drawings in detail wherein like numerals of reference indicate corresponding parts throughout the several views, it will be seen that the horn structure 45 proper comprises a plurality of nested casing bodies or horn members. The outer one of the horn members which may be termed the casing horn or box is indicated by the numeral 1. This box, like the other members associated therewith is of square cross section as

shown in Figure 4, having the top and bottom walls 2 and 3 respectively and the side walls 4 and is of sound proof construction to properly confine and convey the sound to the forward end thereof. The top, bottom and side wall sections of the casing box 1 are so formed that when the same are placed together in side edge relation, a substantially frusto-pyramidal hollow body is set up which is normally supported in horizontal position by the rear bracket 5 secured to one of the walls and the forward supporting foot 6 which is located at the front or large end of the horn. A suitable carrying handle 7 may be secured to the top wall of the casing horn, in the manner shown.

Within the casing box 1 are three nested conducting horn bodies indicated generally by the numerals 8, 9 and 10. The largest of these three bodies, which is indicated by the numeral 8 is of square cross section and is of greater length than the encasing horn 1 and is positioned within the casing 1 with the front or outlet end flush with the front end of the casing. Thus the smaller end of this member extends beyond the rear end of the casing horn 1 as shown in Figure 3. This horn member 8 is also turned in the casing horn 1 in such a manner as to position each of the four side walls thereof cross-ways of each of the angles formed by the walls of the casing horn, each edge of the horn member extending along the longitudinal center of a wall of the casing horn member as shown in Figure 4. Thus there is set up four sounding chambers between the casing and horn member 8. Suitable bracket elements or blocks are interposed between the walls of the casing horn and the edge of the outer one of the three horn members, as indicated at 11, these brackets 11 being located adjacent the rear or constricted end of the horn member 8.

55 Suitable supporting and sound posts 12 extend from each corner of the casing horn adjacent the forward end thereof inwardly to contact with the adjacent wall of the horn member 8. These posts materially reduce the vibration and distortion in the instrument. A suitable binding of thin wood or other material extends about the inner face of the 100

horn member 8 adjacent the forward edge thereof as indicated at 13, and surrounding and extending forwardly of the forward edge of the casing 1 is a binding strip 14 which 5 also serves to form a receiving frame for a grill frame hereinafter described.

Within the outer one of the three horn members is the central one 9 of these members which central horn member is also of 10 square cross section and is of materially less length and width than the member 8 as will be readily seen from reference to Figures 1 and 3. This central horn member 9 is set within the member 8 in such manner as to position 15 each of the four walls thereof substantially parallel with the walls of the horn casing, thus bringing the edges of this center horn member parallel with the longitudinal centers of the walls of the horn member 8 and this 20 member 9 is of sufficient width to cause the edges to bear against the walls of the member 8 when arranged in the position described.

Within and adjacent the inner end of the central horn member 9 is positioned a pair of 25 crossed sound posts 15 and a binding strip or beading of suitable material is formed about this central horn member at the forward edge thereof as indicated by the numeral 16.

30 Within the central horn member 9 is the inner horn member 10 which is of substantially half the length of the central horn member 9 and has its walls arranged in sharper divergent relation from the inner to the outer end 35 than the walls of the horn members 8 and 9. This inner member 10, as above described, is also of square cross section and is so arranged in the member 9 that each of the walls is substantially parallel with the outer horn member 8, thus arranging the edges of this member to extend longitudinally of the central portion of each wall of the central horn member 9. The forward edge of the inner horn member 10 is flush with the forward edges of 45 the other members 8 and 9 and with the casing, horn 1. From the manner of positioning the horn members it will be seen that a plurality of sound chambers is set up, within the casing box, each opening through the 50 front of the instrument.

Positioned within the frame formed by the projecting portion of the binding strip 14 is a double framed grille indicated generally by the numeral 17 and comprising the inner and 55 outer frames 18 and 19 respectively between which is clamped an appropriate piece of material such as cloth or the like indicated by the numeral 20.

Secured to the rear end of the horn casing 60 1 is a tone arm or sounding chamber 21, the outlet end of which opens laterally from the arm in the form of a coupling flange 22 which is designed to be inserted in the small end of the horn casing 1 between the same 65 and the outer one 8 of the three horn members,

this horn member extending into the lower portion of the tone arm as shown in Figure 3. The upper end of the tone arm is provided with a collar 23 in which a phone unit 24 (Figure 2) may be engaged.

70 The structure embodying this invention is preferably formed of a wood suitable to such use such as spruce wood. Applicant prefers to construct the device of this material but it is of course to be understood that he does not limit himself to the use of this material.

75 Having thus described my invention, what I claim is:

1. A loud speaker comprising nested and 80 relatively spaced inner, outer and intermediate horn members of polygonal formation in cross section and arranged to position the corners of the intermediate member at points between the corners of the other members.

2. A loud speaker comprising nested and 85 relatively spaced inner, outer and intermediate horn members of polygonal formation in cross section and of different lengths, the horn members being arranged to position the corners of the intermediate member at points 90 between the corners of the other members.

3. A loud speaker comprising a casing, and 95 nested and relatively spaced inner, outer and intermediate horn members, the casing and horn members being of polygonal formation 100 in cross section and arranged to position the corners of the outer horn member at points between the corners of the casing and to position the corners of the intermediate horn member at points between the corners of the 105 outer and inner horn members.

4. A loud speaker of the character set forth comprising a horn casing of square cross section, a plurality of nested horn like members within said casing each of square 110 cross-sectional design and comprising an outer, an intermediate and an inner member, said outer member being arranged to locate the edges thereof upon the longitudinal center of the casing walls, said intermediate member being arranged to locate its edges upon the longitudinal center of the outer member walls and 115 said inner member being arranged to locate its edges adjacent the longitudinal centers of the intermediate member walls, and a tone arm leading to the inner end of said outer member.

5. A loud speaker of the character set forth comprising a horn casing of square cross section, a plurality of nested horn like members within said casing each of square cross-sectional design and comprising an outer, an intermediate and an inner member, said outer member being arranged to locate the edges 120 thereof upon the longitudinal center of the casing walls, said intermediate member being arranged to locate its edges upon the longitudinal center of the outer member walls and 125 said inner being arranged to locate its edges adjacent the longitudinal centers of the in- 130

termediate member walls, and a tone arm leading to the inner end of said outer member, sound posts connecting the walls of said outer member with the casing, and a sound post structure extending across said intermediate member.

6. A loud speaker of the character set forth comprising a horn casing of square cross section, a plurality of nested horn like members within said casing each of square cross sectional design and comprising an outer, an intermediate and an inner member, said outer member being arranged to locate the edges thereof upon the longitudinal center of the casing walls, said intermediate member being arranged to locate its edges upon the longitudinal center of the outer member walls and said inner being arranged to locate its edges adjacent the longitudinal centers of the intermediate member walls, a tone arm leading to the inner end of said outer member, said intermediate horn member being of materially less length than the outer member, and said inner member being of substantially half the length of the intermediate member.

7. A loud speaker of the character set forth comprising a horn casing of square cross section, a plurality of nested horn like members within said casing each of square cross-sectional design and comprising an outer, an intermediate and an inner member said outer member being arranged to locate the edges thereof upon the longitudinal center of the casing walls, said intermediate member being arranged to locate its edges upon the longitudinal center of the outer member walls and said inner being arranged to locate its edges adjacent the longitudinal centers of the intermediate member walls, a tone arm leading to the inner end of said outer member, said intermediate horn member being of materially less length than the outer member, and said inner member being of substantially half the length of the intermediate member, said inner member having the walls thereof in materially sharper divergent relation than the wall of the other members.

In testimony whereof I affix my signature.

ANDREW DELPH.
